DFS. 2229

Leonard Harris & Paul W. Joiner, of Cincinnati, Ohio,
Letters Patent No. 2229, Dated Dec. 12, 1865.
Design for a Cooking Stove.

The schedule, referred to in these Letters Patent, and making part of the same.

To all whom it may concern:

Be it known that we, Leonard Harris, and
Paul W. Joiner, both of Cincinnati, County of Hamilton, State of
Ohio, have invented a new and improved design for coal and
wood cooking stoves to be known and called the "Range"; and we
do hereby declare that the following is a full and exact description
thereof, reference being had to the accompanying drawings, and
to letters of reference marked theron, wherein letter B shows a
view of the front and side plates of the stove with the doors attached,

What we claim as our invention, and desire to secure by
Letters Patent is the mouldings and scrolls upon the doors, as shown
in annexed drawings, so arranged and combined as to form an
ornamental design for a coal and wood cooking stove.

Witness:

Geo. D. Harris
Frederick T. Seifel.

C. Harris.
Paul W. Joiner.
